DOOR LOCK MECHANISM

William B. Wilson, La Habra, Calif., assignor to National Lock Co., Rockford, Ill., a corporation of Delaware
Filed Dec. 5, 1962, Ser. No. 242,537
12 Claims. (Cl. 70—146)

The present invention relates to a novel builders' lock construction or lock set comprehending three basic unit assemblies including a latch bolt, an outer knob and tube assembly and an inner knob and tube assembly all capable of being combined into plural types of lock sets including a passage door lock for entrance from one room to another by mere turning of the knob, a privacy lock such as employed on the door of a bathroom, bedroom or other room or enclosure having locking means capable of being locked by means of a push button on the inner knob by a person upon entering the room and desiring privacy, and in a privacy lock embodying the push button-actuated locking means but with the outer knob and its tube provided with a key-operated lock permitting entry from the exterior by use of a proper key.

In each form of passage door and privacy locks, the novel lock set requires no housing and is readily and easily adjusted to doors varying substantially in thickness. In each the latch bolt assembly is a preassembled unit adapted for use in each type of lock set disclosed, and the other basic assemblies including the outer knob and its affixed plural tube assembly and the inner knob and its tube assembly are designed and constructed to provide a privacy lock having novel locking mechanism actuated by a push button on the inner knob.

It is an important object of the present invention to provide a novel builders' lock or lock set comprising three basic assemblies including a latch bolt unit, an outer knob having an affixed outer tube and a center tube having a roll-back, and an inner knob and tube, these novel assemblies being so designed and constructed that when combined they provide a passage door lock set for freely retracting the latch bolt by turning of either knob, and also designed to receive novel locking means for locking the latch bolt by depressing a push button on the inner knob and released by turning this inner knob to retract the latch bolt, and in which the outer knob may be provided with a key lock for retracting the locked latch bolt.

The present invention comprehends a novel lock construction in which its basic components are readily assembled for use either as a passage door lock in which the latch bolt is freely retracted by turning of either the outer or inner knob, or when combined with the novel locking means providing a privacy lock in which locking is controlled by a push button on the inner knob and the outer knob is locked against turning movement until the push button is released by the occupant turning the inner knob, or converted to a privacy lock with a push button controlled inner knob and the outer knob key-operated for permitting entry from the exterior by retracting the latch bolt.

A further object of the present invention is the provision of a novel locking mechanism for a basic lock set assembly including an inner knob and tube, an outer knob and tube, and a center tube all so constructed, arranged and combined as to receive and mount the novel locking mechanism for providing a privacy lock set actuated by a push button in the inner knob and with or without a key-operated lock in the outer knob.

Another object of the present invention is the provision of a novel spindle assembly for a door lock comprising an inner tube affixed to an inner knob, an outer tube affixed to an outer knob, and a center tube carrying a roll-back for retracting a latch bolt, said tubes being

2

standardized for use in lock sets of the passage door, privacy and key-lock types.

The present invention further comprehends the provision in a builders' lock or lock set of a novel push button-actuated locking means for controlling operation of the latch bolt.

Further objects are to provide a construction of maximum simplicity, efficiency, economy and ease of assembly and operation, and such further objects, advantages and capabilities as will later more fully appear and are inherently possessed thereby.

In the drawings:

FIGURE 1 is a top plan view showing the novel door lock and latch mechanism combined in assembled relation but removed from the door in which it is mounted.

FIG. 2 is a top plan view of the outer knob and tube assembly including the outer and center tubes combined but with the position of the parts reversed from that of FIG. 1 where the outer knob is shown at the left and with a portion of the knob broken away to show the outer sleeve.

FIG. 3 is a top plan view of the inner knob and its tube and escutcheon and clamp plate assembly, the position being the reverse of the showing in FIG. 1 where the inner knob is shown at the right.

FIG. 4 is a view in end elevation of the inner end of the inner tube assembly of FIG. 3.

FIG. 5 is a view in front elevation of the assembled outside and center tube of the spindle assembly in the position occupied in FIG. 1.

FIG. 6 is a view in end elevation taken from the inner or right-hand end of FIG. 5.

FIG. 7 is a view rear elevation of the tube assembly of FIG. 5.

FIG. 8 is a view in vertical cross section taken on the line 8—8 of FIG. 5 and viewed in the direction of the arrows.

FIG. 9 is a view in vertical cross section taken on the line 9—9 of FIG. 5 and viewed in the direction of the arrows.

FIG. 10 is a view in vertical cross section taken on the line 10—10 of FIG. 7 and viewed in the direction of the arrows.

FIG. 11 is a view in side elevation of the locking bar assembly for the push button-actuated lock, including the locking bar, locking clip, spring cup and the cup spring.

FIG. 12 is a view in end elevation taken from the inner or right-hand end of FIG. 11.

FIG. 13 is a top plan view of a sub-assembly, including the outer tube adapted to project into the outer knob, the center tube, the locking bar, spring cup and the cup spring, push button clip to which is affixed the push button, and the outer clamp plate and studs mounted on the outer tube.

FIG. 14 is a view in end elevation taken from the inner or right-hand end of FIG. 13 but with the push button clip removed.

FIG. 15 is an enlarged view in perspective of the clip for mounting the push button on the inner end of the locking bar.

FIG. 16 is a longitudinal view in horizontal cross section through the assembled lock set but omitting the latch bolt, and showing in plan the lock mechanism including the push button-actuated locking bar assembly, the outer knob and outer tube designed to receive a key lock.

FIG. 17 is a view in vertical cross section taken on the line 17—17 of FIG. 1.

FIGS. 18 to 33, inclusive, disclose the disassembled component parts of the lock mechanism, in which FIG. 18 is a cross-sectional view of the outer knob having an opening for the reception of a key lock cylinder and plug ring; FIG. 19 is a view in side elevation of the lock cylin-

der and plug ring; FIG. 20 is a cross-sectional view of the outer escutcheon; FIG. 21 is a cross-sectional view of the outside clamp plate; FIG. 22 is a side elevational view of a round stud; FIG. 23 is a side elevational view of a square stud received in the tail piece of the housing for the latch bolt; FIG. 24 is a rear elevational view of the outer tube; FIG. 25 is a top plan view of the center tube; FIG. 26 is a side elevational view of the inner tube; FIG. 27 is a cross-sectional view of the inner clamping plate; FIG. 28 is a cross-sectional view of the inner escutcheon; FIG. 29 is an elevational view of one of the two attaching screws; FIG. 30 is a cross-sectional view of the inner knob having an opening for the reception of the push button; FIG. 31 is a disassembled view of a washer, coil spring and spring cup mounted in the center tube; FIG. 32 is a top plan view of the locking bar; and FIG. 33 is a disassembled view of the coil spring, spring cup, locking clip, button clip and push button all assembled on the inner end of the locking bar.

FIG. 34 is a front elevational view of the inner tube.

FIG. 35 is a rear elevational view of the inner tube.

Referring to the disclosure in the drawings, the basic assembly includes a preassembled latch bolt unit including a latch bolt 10 (FIGS. 1 and 17) mounted on the outer reduced end 11 of a bolt retractor 12 having spaced legs 13 and 14 provided with parallel portions received within a tubular housing 15 conformably received and mounted within a bored hole. The housing may be of the mortise or non-mortise type, although in the illustrative embodiment in the drawings is shown a mortise type housing having a face plate 16 anchored in an edge of the door by means of screws or other attaching means 17.

The housing 15 is provided at its inner end with a tail piece 18 forming a closure for the inner end of the housing and to which the tail piece is securely anchored, and a projection 19 having a square or polygonal opening 21 conformably receiving a square stud 22. This tail piece has diametrically opposed slots through which project rearwardly the spaced legs of the sections 13 and 14 of the bolt retractor 12. Beyond the tail piece the legs or sections 13 and 14 are bent outwardly and rearwardly to provide enlargements or expanded portions at 23 and 24, respectively, and are then turned inwardly to provide relatively wide shoulders at 25 and 26 contacted by the widely spaced edges or flanges 27 providing a camming means 28 such as a rollback or portion of increased area or diameter on a center tube hereinafter referred to for retracting the bolt retractor 12 to withdraw the latching bolt 10.

The legs or sections 13 and 14 are extended rearwardly beyond the shoulders 25 with the section 13 bent or formed to provide a longitudinally extending end 29 and the section 14 with a longitudinally extending portion 30, a bridging portion 31 and a return portion 32 extending forwardly and over the end 29 of the section 13. The bolt retractor 12 being of spring metal, the inwardly extending enlargements or flared portions 23 and 24 are adapted to be compressed sufficiently to project them through a bored hole in the edge of the door for assembly or disassembly, and when projected through the hole into operative position automatically expand to the position shown, the extent of expansion being limited by contact between the overlapping ends 29 and 32. An expansion spring 33 spring-biases the latch bolt into projected position and latching engagement.

The arrangement of the extended shoulders or portions 25 and 26 with which either edge 27 of the rollback 28 contacts, provides for a throw of the latch bolt which is substantially greater than that accomplished by prior assemblies.

The basic outer knob assembly consists of an outer knob 34, an outer tube 35, a mating and concentric intermediate or center tube 36, an outer escutcheon 37, an outer clamp plate 38 having an internally threaded round stud 39 and the internally threaded square stud 22 having their plain heads mounted in openings in the clamp plate

38. A notch or slot 40 (see FIG. 16) is cut in the outer clamp plate 38 for a purpose to be later described.

The basic inner knob assembly consists of a knob 41, an inner escutcheon 42, an inner clamp plate 43, and an inner tube 44 (FIGS. 26, 34 and 35). Attaching screws 45 are provided in the inner clamp plate 43 and received in the internally threaded studs 39 and 22. The inner escutcheon 42 is shown provided with openings 46 for access to the screws 45.

10 The outer tube 35 and the mating intermediate or center tube 36 are attached or staked together for simultaneous rotation with the outer knob 34 when the assembly is intended for a passage door lock, the inner tube 44 being also affixed to the tube 36 whereby rotation of either knob rotates the intermediate or center tube 36 and its roll-back 28 to retract the latch bolt 10.

15 The outer tube 35 is provided with longitudinally extending spaced slots 47 and an adjacent transverse slot 48 (FIG. 5), and approximately 180° from the longitudinal portion 49 defined by the slots 47, the tube is provided with a continuous longitudinal slot 51 (FIG. 7). Adjacent the inner end of the slot 51 and at each side thereof, the outer tube is transversely slotted to provide embossments 52 and outwardly from these embossments 25 along the slot 51 this tube 35 is provided with spaced slots 53 to provide intermediate projections 54 for preventing the assembled inner center tube 36 from being withdrawn from the outer tube 35. The outer knob 34 is indented at 55 with the indentation conformably received 30 in the longitudinal slot 51 whereby the outer knob is slidably mounted longitudinally of its tube 35.

20 When the assembly functions as a passage door lock, the portion 49 intermediate the longitudinal slots 47 is indented into an elongated, longitudinally extending indentation 56 between the edges 27 of the rollback 28, whereby the center tube 36 and the outer tube 35 are locked against relative movement or rotation.

25 The center tube 36 is provided at its outer end with a cylindrical part 57 and adjacent thereto and forwardly thereof with a circumferential slot 58 between the part 57 and arcuate projections 59 having a longitudinal slot 61. At the inner end of the center tube 36 forwardly of the rollback 28, the tube 36 is provided with a cylindrical part 62 longitudinally slotted at 63 in alignment with the slot 61 and cut-away at 64 to provide a shouldered portion.

30 When the tube assembly including the outer tube 35 and the center tube 36 are assembled for the reception of a push button locking means, the portion 49 of the outer tube 35 between the spaced longitudinal slots 47 is not indented whereby to permit relative movement between the outer tube 35 and the center tube 36.

35 When the basic assembly is employed in a privacy lock in which the inner knob 41 is provided with a push button assembly, there is inserted in the intermediate tube a washer 65, a coil or expandable spring 66 and an end cap or cup washer 67 having a central aperture 67a, with one end of the spring abutting the washer 65 and the other end received in the cup washer 67. An elongated locking bar or arm 68 has an outer or forward reduced projection 69 received in the aperture of the cup washer, and spaced lateral projections 71 and 72, the projection 71 received and longitudinally movable within the end of the longitudinal slot 51 in the outer tube 35 and a corresponding slot 61 in the center tube, and the projection 72 received and longitudinally movable within the longitudinal slot 63 in the mating tube 36. The extended or inner end portion 74 on the locking bar 68 is provided with a coil or expandable spring 75 bearing at one end against the lateral projection 72 and at its other end received within an apertured cup washer 76, the aperture permitting the extended end portion 74 of the locking bar to project therethrough. A U-shaped locking clip or latch 77 is freely pivoted on the locking bar 68 by means of a pin 78, with the inner inclined end

79 of the locking clip being adapted to drop and engage one of a pair of spaced stops 81 and 82 in the bottom of the center or mating tube 36, whereby when the locking bar is projected inwardly the clip 77 is elevated as it rides over the inclined stop 81 whereupon the end 79 of this clip drops and engages the forward end of this stop and retains the locking bar 68 in its locking position. When the locking bar is released upon turning of the inner knob, the inner tube 44 and this locking bar rotate sufficiently to release the locking clip 77 from the stop 81 and the locking bar 68 is spring-biased to its outer inoperative position against the stop 82.

The inner end 74 of the locking bar 68 is provided with multiple spaced notches 83 each being adapted to receive inturned bifurcations or projections 84 and an extension 84^a on the free end of an adjusting spring clip 85 (FIGS. 15 and 33) which projections straddle the locking bar 68 and the extension is conformably received in a notch 83. The opposite side 86 of this spring clip is provided with an inturned tongue 87 at each side straddling the sides of the locking bar 68 to securely anchor the clip to the locking bar. The opposite or closed end 88 of this spring clip projects into and is affixed to the interior of a push button 89 for depressing the locking bar 68 by a person entering and desiring privacy in the room. The spring clip 85 may engage any one of the notches 83 for adjustment on the locking bar 68.

When the button 89 and the locking bar 68 are in their normal position as shown in FIG. 16, the projection 72 is located in the slot 63 of the center tube 36 to prevent relative rotation therebetween, and the projection 71 is positioned in the slot 61 of the center tube and the aligned slot 51 in the outer tube 35 so that the outer and center tubes rotate together. When the button 89 is depressed and the locking bar 68 moves to the left as viewed in FIG. 16, projection 72 is shifted out of the slot 63 and the projection 71 remains in the slot 51 in the outer tube 35, but enters the slot 40 formed in the stationary clamp plate 38 and the circumferential slot 58 in the center tube 35.

The locking clip or latch 77 is also shifted so that the inner end 79 rides over the inclined stop 81 and drops and engages the forward end of this stop to retain the bar 68 in the locking position. In this locking position, the outer knob 34 and outer tube 35 cannot rotate due to the interengagement of the projection 71 with the slot 51 of the tube 35 and the slot 40 of the fixed clamp plate. However, the inner tube 44 and center tube 36 are connected together by the portion of the inner tube 44 between the slots 99 indented into the slot 63 of the center tube as later described, and the inner knob 41, inner tube 44 and center tube 36 can rotate simultaneously relative to the locking bar 68 and the outer tube 35 as the projection 71 of the locking bar is located in the circumferential slot 58 in the center tube.

Thus, the outer knob 34 is prevented from being rotated to release the push button 89, but all the occupant of the room is required to do to release the push button and its locking bar 68 is to turn the inner knob 41. Rotation of this knob causes rotation of the center tube 36 relative to the locking bar 68 to a sufficient extent that the stop 81 is moved out of the path of the inner end 79 of the latch 77, and the spring 66 urges the locking bar 68 to the right until the projection 72 abuts the edge 64^a of the center tube 36 with the latch 77 moved sufficiently to avoid reengaging the stop 81. Rotation in the reverse direction aligns the slot 63 with the projection 72 to allow movement of the locking bar 68 to its normal position, as shown in FIG. 16, with the inner end 79 of the latch 77 engaging the stop 82 in the center tube 36.

When the above described privacy lock is intended for use in an exterior door or for an enclosure accessible from the outside of the door by means of key-operated lock in the outer door knob 34, all that is required is to install in an opening 91 in the outer knob a standard or

conventional key-operated lock plug and cylinder 92 and plug ring 93 which is inserted into the outer tube 35 with its lateral projection 94 slidably received in the longitudinal slot 51 in this tube.

5 To unlock from the outside, the door previously locked by depressing the push button 89 at the interior, requires insertion and turning of the proper key in the cylinder lock 92. This rotates the plug ring 93 having its projected end received in the slotted outer end 90 of the center tube 36 and carries therewith the center tube which rotates within the outer tube 35. This causes its rollback 28 in turning to retract the latch bolt 10. It should be noted that in the locked position as mentioned above and in which the clip or latch 77 engages behind the stop 81, the locking bar 68 is projected outwardly or forwardly whereby its projection 72 leaves the slot 63 in the center tube 36 permitting the center tube to be rotated relative to the locking bar 68. Rotation of the center tube will release the clip or latch 77 on the bar 68 from the stop 81 in the center tube and the projection 72 abuts the edge 64^a of the center tube 36. When the key is turned back to release it from the lock, the center tube 36 is returned to normal position with the slot 63 aligned with the projection 72. As the clip 77 has been released from the 10 stop 81, the locking bar 68 is spring-biased to its unlocked or inoperative position with the projection 72 entering the slot 63 and the clip 77 abutting stop 82.

As shown in FIGS. 26, 34 and 35, the inner tube 44 is provided with an elongated longitudinal slot 95, and 30 closely spaced transverse notches 96 opening in the slot 95 to provide tongues 97 adapted to be indented into the inner end of the elongated indentation 56 in the center tube 36 to prevent the assembled inner tube from being withdrawn from the assembly. The inner tube 44 is also 35 provided with a transverse slot 98 and longitudinal slots 99 on the side opposite the longitudinal slot 95. The portion of the tube 44 between the slots 99 is adapted to be indented into the longitudinal slot 63 of the center tube 36 to lock the inner tube 44 and the center tube 36 40 against relative rotation. Stops or abutments 52 like those on the outer tube 35 are also provided.

The transverse slot 98 like the slot 48 in the outer tube 35 is adapted to conformably receive an outer projection 101 on an expanding ring 102 positioned within 45 each tube 35 and 44, one such ring being shown in the outer tube 35 in FIG. 16. The neck of each knob 34 and 41 is provided with a similar transverse slot whereby when a knob is assembled on its tube and its slot is aligned with a slot in its tube through which extends the depressed projection 101, this spring-biased projection enters the slot in the knob and locks the knob to its tube. The inner knob 41 is also provided with an indentation 55 like that of the outer knob 34 received in the longitudinal slot 95 of the inner tube 44 for aligning the knob and retaining it against rotation on its tube.

The embossments 52 provide stops or abutments for 50 locating the outer and inner tubes 35 and 41 relative to the outer and inner clamp plates 38 and 43, respectively.

When the novel basic assembly is employed as a passage door lock, the inner and outer knobs may be devoid of an opening for it requires no supplemental locking means for the latch bolt, although an inner or outer knob having an opening may be used and the opening provided with a suitable cap 103 as shown in FIG. 16 to provide a 55 closure.

In the combining of the basic assemblies of the lock set in openings in the door, the latch bolt unit is inserted in a conforming opening in the edge of the door. Next the 60 outer knob assembly (FIG. 2) with its outer tube and affixed center tube is inserted with the square stud 22 projecting through the square opening 21 in the tail piece 19 of the latch bolt. Then the inner knob assembly is mounted in position with the attaching screws 45 inserted 65 from the interior of the inner clamp plate and threaded

into the studs 22 and 39. Thus when these screws are tightened the inner and outer clamping plates are drawn tightly against the door to provide a rigid assembly which requires no encompassing housing.

Having thus disclosed my invention, I claim:

1. A lock construction for a door or other closure, comprising a latch bolt assembly having a housing provided with a tail piece having a polygonal opening and a rearwardly projecting bolt retractor, an outer knob unit including an outer knob, an outer tube on which the knob is mounted, a clamp plate and escutcheon mounted on said tube with said clamp plate provided with rearwardly projected attaching studs one of which is of polygonal cross section conformably received and projected through the polygonal opening of said tail piece for retaining the latch bolt assembly in operative position, and a center tube having its outer end received in and connected to said outer tube and provided with a rollback intermediate its ends, and an inner knob assembly including an inner knob and an inner tube carrying an inner clamp plate and an escutcheon, said inner tube receiving therein and connected to the inner end of said center tube, and said inner clamp plate being connected to said outer clamp plate by attaching means insertable through said inner clamp plate and having adjustable engagement with said studs for drawing said clamp plates tightly against the opposite sides of the door and accommodating doors of varying thickness.

2. A lock construction for a door or other closure, comprising a latch bolt assembly having a housing and a rearwardly projecting bolt retractor of flexible metal including spaced legs in the housing which are flared outwardly and rearwardly and then turned inwardly to provide relatively wide shoulders at the exterior of said housing, an outer knob unit including an outer knob, an outer tube on which the knob is mounted, an outer clamp plate and escutcheon mounted on said tube with said clamp plate provided with attaching studs, and a center tube having its outer end received in and connected to said outer tube, said center tube being cut away intermediate its ends at a point aligned with and on the side opposite said latch bolt assembly to provide camming surfaces forming a rollback, said legs of the retractor extending around said rollback with the shoulders adapted to engage the camming surfaces on the side of the rollback away from said latch bolt, and an inner knob assembly including an inner knob and an inner tube carrying an inner clamp plate and an escutcheon, said inner tube receiving therein and connected to the inner end of the center tube, and said inner clamp plate being connected to said outer clamp plate by attaching means insertable through said inner clamp plate and having adjustable engagement with said studs for drawing said clamp plates tightly against the opposite sides of the door.

3. A lock construction for a door or other closure in which locking is effected by a push button, comprising a latch bolt assembly, an outer knob assembly including an outer tube and knob mounted thereon, an intermediate tube having a rollback operatively connected to said latch bolt assembly with an end of the intermediate tube telescoped within said outer tube, an inner knob assembly including an inner tube and an inner knob mounted thereon, said inner tube receiving therein and secured to the inner end of the intermediate tube, an outer clamp plate and escutcheon on the outer tube and an inner clamp plate and escutcheon on the inner tube, said clamp plates being secured together and held stationary on a door and mounting said inner, outer and intermediate tubes for rotation, and a push button-actuated locking means including a spring-biased locking bar projecting through said inner tube and into said intermediate tube, a locking clip pivotally mounted on said locking bar and a pair of spaced stops on the interior surface of the intermediate tube one of which is engaged by said clip for locking the bar in

5 projected position, and a laterally extending projection on the inner end of the locking bar, said outer tube and one end of said intermediate tube having coinciding longitudinal slots receiving said projection so that the inner and intermediate tubes and the locking bar rotate simultaneously in the retracted position of the locking bar, said outer clamp plate having a slot normally aligned with the slot in the outer tube to receive the projection when the locking bar is in locked position to prevent rotation of the outer tube and knob and retraction of the latch bolt.

10 15 20 25 30 35 40 45 50 55 60 65 70 75 80 85 90 95

4. A lock construction as set forth in claim 3, in which a second lateral projection is formed on said locking bar spaced from said first projection, and said intermediate tube has a longitudinal slot at the opposite end thereof receiving said second projection when the locking bar is in unlocked position, said projection being free of said slot when said bar is in locked position.

5. A lock construction as set forth in claim 4, in which said intermediate tube has a circumferential slot therein communicating with said longitudinal slot and aligned with said first mentioned projection on said locking bar in the locked position so that the intermediate tube may be rotated relative to said locking bar and independently of the outer tube.

6. A lock construction as set forth in claim 5, in which the outer knob and tube are provided with a keyoperated locking means operatively connected with said intermediate tube to rotate said intermediate tube relative to said locking bar in its locked position to release said locking bar from its locked position.

7. A lock construction for a door or other closure comprising a latch bolt assembly having a housing provided with a tail piece having a polygonal opening and a rearwardly projecting flexible bolt retractor, an outer knob assembly including an outer knob, an outer tube on which the knob is mounted having a longitudinal slot therein, a clamp plate and escutcheon mounted on said tube with said clamp plate provided with rearwardly projecting attaching studs one of which is of polygonal cross section conformably received and projected through the polygonal opening of said tail piece for retaining the latch bolt assembly in operative position, said clamp plate having a slot therein normally aligned with the slot in the outer tube, and a center tube having its outer end received in said outer tube and having a cut-out providing a rollback intermediate its ends, said center tube having a longitudinal slot at each side of the cut-out normally aligned with the slot in the outer tube and a circumferential slot, an inner knob assembly including an inner knob and an inner tube carrying an inner clamp plate and escutcheon, said inner tube receiving therein and connected to the inner end of the center tube, said inner clamp plate being connected to said outer clamp plate by attaching means insertable through said inner clamp plate and having adjustable engagement with said studs for drawing said clamp plates tightly against the opposite sides of the door, and a reciprocable locking bar extending from said inner knob through said inner and center tubes, a push button in said inner knob actuating the inner end of said bar to manually reciprocate the locking bar from a first position to a second position, and locking means retaining said bar in its second position, said locking bar including a lateral projection intermediate its ends which projects into the slot in the center tube adjacent the inner tube in said first position and is moved clear of the slot in said second position, and a relatively longer lateral projection adjacent the outer end of said bar extending into the aligned longitudinal slots in the outer and center tubes connecting the outer and center tubes for rotation in the first position and extending into the aligned slots in the outer tube and the outer clamp plate and the circumferential slot in the center tube for retaining the outer tube and knob against rotation in the second position.

8. A lock construction as set forth in claim 7 in which said locking means for said bar includes a locking clip

pivotedly mounted on said locking bar and spaced stop members on the interior surface of said center tube, said locking clip adapted to engage one of the two stop members and to be released from the stop member for said second position by rotation of the center tube relative to said locking bar and locking clip.

9. A lock construction as set forth in claim 8, including spring-biasing means to urge said locking bar to its first position.

10. A lock construction as set forth in claim 9, in which the inner, outer and center tubes and the locking bar rotate simultaneously upon rotation of a knob when the locking bar is in its first position, and when said locking bar is in its second position said outer tube and knob and said locking bar are held against rotation while said inner tube and knob and said center tube are capable of rotation relative to said outer tube and locking bar to release said locking clip and return said locking bar to said first position.

11. A lock construction as set forth in claim 10, including a key-operated lock in said outer knob operatively connected to said center tube to rotate said tube relative to said locking bar to release said bar from its second position and simultaneously permit the bolt to be retracted.

12. A lock construction for a door or other closure comprising a latch bolt assembly having a housing provided with a rearwardly projecting flexible bolt retractor, an outer knob assembly including an outer knob, an

outer tube on which the knob is mounted, a clamp plate and escutcheon mounted on said tube with said clamp plate provided with rearwardly projecting attaching studs, and a center tube having its outer end received in said outer tube and having a cut-out providing a rollback intermediate its ends, an inner knob assembly including an inner knob and an inner tube carrying an inner clamp plate and escutcheon, said inner tube receiving therein and connected to the inner end of said center tube, said inner clamp plate being connected to said outer clamp plate by attaching means insertable through said inner clamp plate and having adjustable engagement with said studs for drawing said clamp plates tightly against the opposite sides of the door, and reciprocable means operatively connecting said outer and center tubes for simultaneous rotation in a first position and for retaining said outer tube and knob against rotation but allowing rotation of the center tube relative to the outer tube in a second position.
